UNITED STATES PATENT OFFICE.

WILLIAM W. ALLEN, OF CORNELL, ILLINOIS.

WATER-KEY FOR MUSICAL INSTRUMENTS.

942,429.

Specification of Letters Patent.

Patented Dec. 7, 1909.

Application filed February 4, 1909. Serial No. 476,007.

To all whom it may concern:

Be it known that I, WILLIAM W. ALLEN, a citizen of the United States, residing at Cornell, in the county of Livingston and State 5 of Illinois, have invented certain new and useful Improvements in Water-Keys for Musical Instruments, of which the following is a specification.

This invention relates to musical instruments and has special reference to that class 10 of instruments which are known as wind instruments.

The invention has for an object the formation of an improved water valve in connection 15 with the same by means of which the moisture collected in the tube of the instrument may be released from the same.

The invention has for another object the provision of an absorber in connection with 20 instruments of this character by means of which the moisture collected in the tubes is removed to prevent the instrument from changing in pitch during the playing of long passages during which time it is impossible 25 for the performer to open the water valve.

The invention further designs an attachment 30 to a wind instrument which will prevent the water emitted from the vent in the tube from being sprayed against the adjacent tubes of the instrument and collecting on 35 the outer faces thereof, thereby tarnishing or corroding the same which impairs the appearance of the instrument.

For a full understanding of the invention 40 reference is to be had to the following description and accompanying drawings, in which,

Figure 1 is a side elevation disclosing a 45 fragmentary view of a wind instrument having the improved water key affixed thereto. Fig. 2 is a detailed sectional view of the key showing a fragmentary view of the vent of a wind instrument. Fig. 3 is a perspective of the improved key, the operating lever being broken away. Fig. 4 discloses a modified securing means for the key upon the vent of the wind instrument.

Corresponding and like parts are referred 50 to in the following description and indicated in all the views of the drawings by the same reference characters.

Referring to the drawings the numeral 10 designates the slide of a wind instrument 55 which is employed in tuning the same and which comprises a metallic tube which is

bent into U-formation and inserted within the open extremities of parallel tubes upon the instrument. The slide 10 is provided in the usual manner with a vent 11 which is 60 projected outwardly therefrom and through which the moisture collected within the slide 10 is ejected. The slide 10 is also provided with ears 12 which extend outwardly therefrom and are spaced a short distance from the vent 11 to support a lever 13 which is intermediately fulcrumed between the ears 12. A spring 14 is employed which is disposed between the slide 10 and lever 13 for the purpose of normally retaining the outer 65 extremity of the lever 13 in an outward position. The inner extremity of the lever 13 is provided with a closure 15 which carries an inwardly extended annular flange 16 which is adapted for engagement about the 70 outer extremity of the vent 11 when the closure 15 is brought into engagement therewith. The closure 15 is provided at its outer end with a metallic strip 17 which is secured upon the outer face of the cap adjacent the lever 13, the strip 17 being curved circularly upon itself at its outer extremity to support a pintle 18 upon which is hingedly disposed a bar 19. The bar 19 is extended diametrically across the outer open end of 75 the closure 15 and is provided with an inwardly curved flange 20 for engagement beneath a lip 21 formed upon the outer extremity of a leaf spring 22 disposed upon the outer face of the closure 15 at a point 80 diametrically opposite from the metallic strip 17. The leaf spring 22 is curved outwardly at its upper extremity and is adapted for engagement against the flange 20. The bar 19 is provided with a spring 23 which is 85 disposed about the pintle 18 and engaged at its opposite extremities against the inner face of the bar 19 and inner wall of the closure 15. The spring 23 is employed for the purpose of normally holding the bar 23 in an 90 outward position. The closure 15 is provided with a quantity of absorbent material 24 which may be cotton or the like and which is detachably disposed in the same for the ready removal thereof when the same is 95 thoroughly saturated with the moisture collected in the slide 10 and passed through the vent 11.

In the modification disclosed in the drawings the vent 25 is provided with a threaded 100 outer portion which is adapted to receive a flange 26 carried upon the inner end of the

closure 27. The flange 26 is provided about its inner edge with a threaded portion which is adapted for engagement with the threaded portion of the vent 25 to secure the closure 27 in position.

The operation of the device is as follows: As the instrument is employed the moisture collects within the slide 10 and passes through the vent 11 into the absorbent ma-

10 terial 24 where it is retained and prevented from accumulating within the slide 10. The cap 15 is fitted closely against the vent 11 by means of the spring 14 through the medium of the lever 13 for the purpose of preventing 15 the escape of air from the tubes of the instrument and for preventing the escape of any moisture which is passed from the vent 11 into the closure 15. It is seen from this construction that a considerable amount of 20 moisture can be collected within the closure 15 by means of the absorbent material 24 before the tone or pitch of the instrument will be impaired by the collection of such moisture within the slide 10. With the employment 25 of this device the performer is enabled to play long passages of music without the disadvantage of having the instrument produce a broken tone, which is caused by the accumulation of water or moisture within 30 the tubes, the device enabling the performer to continue through such passages without the necessity of opening the vent 11 to eject such moisture. The absorbent material 24 may be withdrawn from the closure 15 for 35 the purpose of renewing the same by releasing the flange 20 of the bar 19 by pressing the leaf spring 22 inwardly at its upper extremity when the spring 23 will force the bar 19 in an outward position and admit of 40 the withdrawal of the absorbent 24.

In the modification the closure 27 is secured upon the vent 25 by threaded engagement therewith and is removed therefrom by the rotation of the same for the purpose 45 of renewing the absorbent which is placed therein. In a device of this nature and construction it is readily seen the closure may be positioned upon any portion of a wind instrument within which the moisture is 50 adapted to collect.

Having thus described the invention, what is claimed as new is:—

1. A device of the class described comprising a tube, a vent formed in said tube, a lever pivotally disposed upon said tube adjacent the vent formed therein, a closure carried upon the inner extremity of said lever for engagement about the vent, said closure having an outer open end a spring disposed

between the tube and said lever for holding 60 said closure about said vent, an absorbent material disposed in said closure, a bar hingedly connected at one side of said closure and extended diametrically across the open outer end thereof and a leaf spring 65 disposed on said closure for engagement with said bar to hold the same in a closed position.

2. A device of the class described comprising a wind instrument, a tube on said 70 instrument, a vent formed in said tube, a closure adapted for engagement over said vent, a flange inwardly extended from the inner end of said closure for engagement about said vent, an absorbent material positioned in said closure, a bar pivotally disposed across the outer end of said closure 75 for retaining said absorbent material in position and means for securing said closure against said vent.

3. A wind instrument provided with a tube having a vent formed therein in combination with a closure detachably positioned over the vent on said tube, an absorbent disposed in said closure and means 85 carried by said closure for removably retaining said absorbent therein.

4. In combination with a wind instrument provided with a tube having a vent formed therein of a spring actuated lever 90 mounted on said tube adjacent said vent, a closure carried by said lever having the inner end thereof reduced to engage said vent, an absorbent engaged in said closure and a bar detachably engaged over the outer end 95 of said closure for retaining said absorbent in position.

5. A wind instrument provided with a tube having a vent formed therein in combination with a spring-actuated lever 100 fulcrumed in juxtaposition to said vent, a closure disposed on said lever, a flange inwardly extended from the inner edge of said closure for engagement about said vent, a bar hingedly disposed at one side of said 105 closure at the outer edge of the same, an inwardly curved flange formed upon the free extremity of said bar, a leaf spring carried upon the opposite side of said closure, a lip formed on said leaf spring to engage said 110 flange and an absorbent detachably retained in said closure by said bar.

In testimony whereof I affix my signature in presence of two witnesses.

WILLIAM W. ALLEN. [L.S.]
